UNITED STATES PATENT OFFICE.

MATTHEW A. HANSE, OF BARNESVILLE, OHIO.

DESIGN FOR A PLATE OR SIMILAR ARTICLE.

Application filed May 31, 1928. Serial No. 26,936. Term of patent 3½ years.

To all whom it may concern:

Be it known that I, MATTHEW A. HANSE, a citizen of the United States, residing at Barnesville, in the county of Belmont and State of Ohio, have invented a new, original, and ornamental Design for a Plate or Similar Article, of which the following is a specification, reference being had to the accompanying drawing, forming a part thereof.

The figure is a plan view of a segment of a plate showing my new design, the re-

mainder of the design not shown, being simply a repetition of what is shown, and a portion of the plate being broken away because of the prescribed width of the sheet of drawing required.

I claim:

The ornamental design for a plate or similar article, as shown and described.

In testimony whereof I affix my signature.

MATTHEW A. HANSE.
